UNITED STATES PATENT OFFICE.

ALBERT SANFORD, OF OSHKOSH, WISCONSIN.

CANT-HOOK.

SPECIFICATION forming part of Letters Patent No. 408,755, dated August 13, 1889.

Application filed November 12, 1888. Serial No. 290,593. (No model.)

To all whom it may concern:

Be it known that I, ALBERT SANFORD, of Oshkosh, in the county of Winnebago and State of Wisconsin, have invented certain new and useful Improvements in Cant-Hooks; and I do hereby declare the following to be a full, clear, and exact description of the same, reference being had to the accompanying drawings, forming a part of this specification, and to the figures and letters of reference marked thereon.

My invention has for its object to provide a cant-hook in which the handle-socket and the pick or pike are formed integral and so shaped as to give the maximum amount of strength and durability to the implement and at the same time render it more generally available and effective than those heretofore provided.

In the accompanying drawings, Figure 1 represents a front view of an implement embodying my invention. Fig. 2 is a rear view of the combined socket and pick; Fig. 3 a side view, Fig. 4 a top view, and Fig. 5 a longitudinal sectional view, of the same. Fig. 6 is a cross-sectional view taken on the line xx , Fig. 1.

Similar letters of reference in the several figures indicate the same parts.

The letter A indicates my combined socket and pick. It is made of malleable iron, malleable iron and steel, or of cast-steel; but in either case it is formed of a single piece and in the form of a shell into which the handle is adapted to be driven. By forming it hollow nearly down to the end of the pick and making the walls comparatively thin I am enabled to get a more even annealing of the metal, and thus secure lightness without a sacrifice of strength.

The face of the pick portion is flattened, as shown at a , and is preferably very slightly concaved in the direction of its greatest length, as shown in Fig. 3, while one or more ribs or beads b , extending to the chisel-edge, are preferably formed upon it to prevent slipping when the pick is inserted under a log to raise the latter and at the same time give it a longitudinal movement. The back 45 of the pick is curved or convexed in the direction of its greatest length, as shown at c , Figs. 2

and 3, to give a better leverage when prizing, and is convexed in cross-section, as shown in Fig. 6 at f , to impart to it greater strength when used as a pry, and is flattened down at 55 the end to the broad chisel-shaped edge of the pick, as shown at g .

The general flattening of the pick at both front and rear enables a person to more conveniently use the implement in places where 60 a thin edge is necessary in order to catch a hold, as between logs or between a log and skid. Near the end of the pick and on the side thereof a stud or projection h is formed for co-operation with the swinging hook B, 65 Fig. 1, in the usual manner.

The interior of the socket is preferably provided with tapering or wedge-shaped ribs i (see Fig. 5) for assisting in holding the socket onto the handle, and way down in the 70 pick portion of the casting one or more wedge-shaped projections k are provided for the purpose of entering the end of the handle when driven in, and spreading it, so as to make the connection more secure. Opposite 75 this projection or projections k the wall of the casting is slightly chambered out, as at k' , to permit of the greater expansion of the wood of the handle when it is spread. The projection k extends from side to side of the socket, 80 making a sort of partition, which adds very materially to the strength of the pick.

The upper end of the socket is split at l and provided with lugs $m m$, through which passes the bolt n , upon which the hook B is 85 pivoted. By tightening this bolt the socket is drawn closely about the handle, as will be readily understood.

Having thus described my invention, what I claim as new is—

1. The combined socket and pick formed of a single piece hollow down to the point to receive the wooden handle, having the flattened face a extending up on the outside of the hollow portion, and the convexed back portion 95 terminating in the chisel-shaped edge, substantially as described.

2. The combined socket and pick formed of a single piece made hollow to receive the wooden handle and having the flattened face a on the outside provided with the rib or ribs b , and the convex back portion terminating in

a chisel-shaped edge, substantially as described.

3. The combined socket and pick made hollow to receive the wooden handle and having the flattened face *a*, with the rib or ribs *b* thereon, the convex back portion terminating in a chisel-shaped edge, the pointed projection on the side, and the hook co-operating therewith, substantially as described.

10 4. The combined socket and pick formed in a single piece made hollow to receive the han-

dle having the split upper end, the wedge-shaped ribs at the upper end and the wedge at the lower end of the hollow portion, the flattened face *a*, the convexed back portion *c*, 15 and terminating in the chisel-shaped edge, substantially as described.

ALBERT SANFORD.
